UNITED STATES PATENT OFFICE.

HENRY C. SWAN, OF OSHKOSH, WISCONSIN.

DESIGN FOR A FIFTH-WHEEL.

SPECIFICATION forming part of Design No. 25,760, dated July 7, 1896.

Application filed April 4, 1896. Serial No. 586,261. Term of patent 14 years.

To all whom it may concern:

Be it known that I, HENRY C. SWAN, of Oshkosh, in the county of Winnebago and State of Wisconsin, have invented a new and original 5 Design for Fifth-Wheels, of which the following is a full, clear, and exact description.

The accompanying drawing shows in perspective view the upper circle-plate of a fifth-wheel embodying my design, which consists 10 in such circle-plate having the shape illustrated in said drawing and herein described.

The wearing-plate 2 of the upper circle-plate is made in the form of a circular arc, having a cross-piece 3, with a plate 4 extend-

ing rearwardly from the middle thereof and 15 perforated at 5. From the ends of the cross-piece 3 bars 6 extend horizontally rearwardly and then forwardly in heart shape to the plate 4.

I claim—

The design for fifth-wheels, substantially as herein shown and described.

In testimony whereof I have hereunto set my hand.

HENRY C. SWAN.
